UNITED STATES PATENT OFFICE.

JACOB G. HIEB, OF OAKLAND, CALIFORNIA.

DIRECTION SIGNAL FOR MOTOR VEHICLES.

1,416,027.

Specification of Letters Patent. Patented May 16, 1922.

Application filed July 11, 1921. Serial No. 483,655.

To all whom it may concern:

Be it known that I, JACOB G. HIEB, a citizen of the United States, residing at Oakland, county of Alameda, State of California, have invented certain new and useful Improvements in Direction Signals for Motor Vehicles; and I do declare the following to be a full, clear, and exact description of the same, reference being had to the accompanying drawings, and to the characters of reference marked thereon, which form a part of this application.

This invention relates to improvements in direction signals for motor vehicles, to be used for giving signals in place of the hand as ordinarily employed.

The principal object of this invention is to provide a device of this character which may be extended to any one of three positions—at an upward angle, horizontally, or at a downward angle, and which when neutral or not in use will fold up or contract to occupy but a very little space.

A further object is to provide a hand actuating means for the signal with but a single hand-moved member for both extending the signal and for moving it to any one of the three possible positions, as may be selected at will.

30 A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

40 Fig. 1 is a perspective outline of the driving compartment of an automobile, showing my improved signal installed thereon, the signal being in a horizontally extended position.

45 Fig. 2 is a detached elevation of the signal and its operating mechanism, placed in alinement for the sake of convenience of showing the operation, the signal being extended horizontally in full lines, and controlled in dotted lines.

50 Fig. 3 is a similar view, the signal being extended and positioned at a downward angle to a horizontal plane.

55 Referring now more particularly to the

characters of reference on the drawings, the numeral 1 denotes a casing adapted to be attached to the windshield 2 or similar member of the car by means of any suitable form of clamp.

60 This casing is an enclosure throughout, except at its outer vertical end, where it is open, as at 1^a.

Pivotedly mounted in the casing is the signal member 3, made of a plurality of short metal strips 4, all pivotally connected together to form a structure commonly known as a "lazy tongs", which is such that a pressure on the ends will contract the same so that all the bands lie substantially against and 70 parallel to each other, and a pulling force on said ends will expand or cause an extension of the structure. The same effect is gained by making the bands 5 at the inner end of the structure free at their outer ends, 75 when a force tending to cause such ends to move apart will contract the structure, and a driving together of such ends will extend the same. The pivotal connection of the signal structure with the casing is preferably had where the bands or arms 5 cross each other, as at 6.

To effect the expanding and contracting movement of the lazy tongs signal from a point convenient to the driver of the car, I 85 provide a casing 7 preferably attached to the steering column 8 of the car, in which casing is pivotally a short lazy tongs structure 9, consisting of a pair of crossed arms 10, pivoted to the casing at their intersection as at 11. The ends of the arms 10 nearest the arms 5 are connected to the latter in crossed relation by flexible wires 12, enclosed in flexible tubing 13, in order that said wires may be pushed on and impart movement to 95 the arms 5 without buckling.

The opposite ends of the arms 10 are connected to each other by short links 14 which intersect and are pivoted together at that point, such pivotal connection being formed 100 with a handle projecting through a three-way slot 16 in the casing 7. This slot has three portions A, B and C, converging at the end thereof farthest from the pivotal mounting 11 of the structure 9. The portion 105 A extends in the plane of a line passing through the axial points 11 and 15; the portion B branches to one side of the portion A, and at an acute angle thereto, the portion C an equal distance and angle on the other side 110

of the portion A. The portions B and C are preferably curved somewhat and all the said portions terminate in substantially a common plane at right angles to the axial plane 5 aforementioned.

Fixed in the casing 7 intermediate the points 11 and 15 is a pin 17, projecting into the path of movement of the arms 14.

In order that the signal may be visible at 10 night, an electric light 18 may be mounted at the outer end of the structure 3, which may be wired in a circuit in any suitable manner, and which with the signal 3, will be concealed within the casing 1 when the 15 signal is contracted.

When in the latter position, the signal may be further protected against dust etc. by means of a spring-hinged door 19 on the casing and normally closing the opening 1a.

20 This door is automatically opened by the extending movement of the signal 3, and closes of itself when the signal is withdrawn into the casing.

The operation of the device is as follows:—When the handle 15 is moved outwardly to the point of convergence of the slot-portions, the arms 10 will be symmetrically positioned with respect to the axial line between the points 11 and 15, and will 25 then be moved close together and away from the handle.

A pushing pressure is thus imparted to the wires 12 causing the arms 5 to be spread apart, which in turn causes the signal 3 to be 30 fully contracted and lie concealed in the casing 1. When the handle 15 is then pushed the length of the slot A, the signal 3 will be 35 extended horizontally since as the slot A lies in the plane of a line drawn through the points 11 and 15, the movement imparted to the arms 10 will be equal. When the handle is retracted however to the point of convergence of the slots and then moved 40 into one of the branches, as for instance the portion C, as shown in Fig. 3, the arm 10 then opposite to said slot C is prevented from but slight movement by reason of its 45 striking against the pin 17. The expanding or extending movement to and the corresponding arm 5 on the signal is likewise 50 held against movement. The majority of the expanding or extending movement of the signal 3 is therefore had with the movement of the other arm 10 and the corresponding 55 signal-arm 5 alone, causing the signal to be not only fully extended to lie at a considerable downward angle with respect to a horizontal plane. With the movement of the handle 15 through the slot B, the reverse 60 conditions obtain, and the signal 3 is extended to lie at an upward angle.

On account of the flexibility of the wires 12, it makes no difference in the operation of the device as to the relative positions of 65 the members 3 and 9, as long as the wires 12

cross at some point in their extent, so as to connect relatively opposed ones of the arms 5 and 10.

The arms 5 and 10 can be connected direct without crossing the wires, but with such a 70 lay-out the signal is turned down when the handle is moved into the right hand slot B, which is not desired, since a movement of the handle to the right should also indicate a turn of the vehicle to the right, which 75 would not be the case with such an arrangement of the wires. Also, for a given amount of extension of the signal, the angle of setting obtained would be too great for convenience.

80 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 90

Having thus described my invention, what I claim as new and useful and desire to secure by Letters Patent is:

1. A direction signal for motor vehicles comprising a lazy tongs signal structure 95 pivoted to a fixed member of the vehicle, and a hand actuated means for contracting and extending said structure and for giving the same any one of a number of predetermined angular settings in a common vertical plane 100 while so extending said structure.

2. A direction signal for motor vehicles comprising a lazy-tongs structure pivoted to a fixed member on the vehicle, manually operable means for contracting and extending the same, means whereby the signal may be extended to any one of a number of different angular settings, in a common vertical plane and means whereby when the signal has been so extended the angular position 110 cannot be altered until the signal is again contracted.

3. A direction signal for motor vehicles comprising a lazy tongs signal structure pivoted to a fixed member of the vehicle and 115 a common hand actuated means operatively connected to said structure for both extending and contracting the latter, and for causing the same to assume any one of a number of predetermined angular positions in a common vertical plane simultaneous with the extending thereof.

4. A direction signal for motor vehicles comprising a lazy tongs signal structure pivoted to a fixed member of the vehicle, 125 another lazy tongs structure independent of the first named structure and adapted to be manually contracted and extended and being operatively connected to said signal structure and means whereby said manually 130

actuated structure may be manipulated to impart contracting and extending movement to the signal structure and at the same time cause the latter to lie in any predetermined 5 angular setting coincident with such extension thereof.

5. A direction signal for motor vehicles comprising a lazy tongs signal structure pivoted to a fixed member of the vehicle, an-
10 other lazy tongs structure independent of the first named structure and adapted to be manually contracted and extended and being operatively connected to said signal struc-
15 ture, a handle on said independent structure whereby to contract and extend the same, and a fixed casing in which said latter struc-
ture is mounted, said casing being provided with converging and communicating slots positioned at predetermined angles relative
20 to each other and in which the handle rides.

6. A direction signal for motor vehicles comprising a lazy tongs signal structure pivoted to a fixed member of the vehicle, a fixed casing, a lazy tongs structure inde-
25 pendent of the signal structure, said inde-
pendent structure comprising a pair of inter-
secting arms pivoted in the casing at their point of intersection, and a pair of links pivoted to certain ends of the arms and
30 pivotally connected to each other, operative connections between the opposite ends of the arms and the signal structure, a handle at the pivotal connection of the links with each other, the casing being provided with

a slot extending in the plane of a line drawn 35 through the arm and handle pivots and through which the latter passes, branch slots communicating with the first named slot at one end thereof and at an angle thereto, and means whereby when the handle is moved 40 through one of the last named slots the signal structure will be extended and positioned at a predetermined angle.

7. A direction signal for motor vehicles comprising a lazy tongs signal structure 45 pivoted to a fixed member of the vehicle, a fixed casing, a lazy tongs structure inde-
pendent of the signal structure, said inde-
pendent structure comprising a pair of inter-
secting arms pivoted in the casing at their 50 point of intersection, and a pair of links pivoted to certain ends of the arms and pivotally connected to each other, operative connections between the opposite ends of the arms and the signal structure, a handle at 55 the pivotal connections of the links with each other, the casing being provided with a slot extending in the plane of a line drawn through the arm and handle pivots and through which the latter passes, branch slots 60 communicating with the first named slot at one end thereof and at an angle thereto and a pin fixed in the casing intermediate the arm and handle pivots and projecting into the plane of the arms. 65

In testimony whereof I affix my signature.

JACOB G. HIEB.
